CARTON

Jack Lang, New York, N. Y., assignor to Makdon, Inc., New York, N. Y., a corporation of New York

Application January 21, 1949, Serial No. 71,897

6 Claims. (Cl. 229—36)

1

This invention relates to a carton which may be used for packaging and display of cosmetics and other commodities. The carton is adapted to hold a platform for displaying the commodities. When the carton is closed, it resembles a lady's handbag. It may be equipped with a handle and used as a carrying case.

The carton may be readily assembled from a single blank of material, or optionally may be assembled from two or more blanks. The carton is formed with a reinforced front support member. The platform is usually a separate item and may be used apart from the carton for display purposes, but optionally the platform is made integral with the carton.

The front support member of the carton adds to its rigidity, and also serves as a convenient means for securing the handle to the carton.

Other objects and advantages of this invention will become apparent from the following description.

Fig. 1 is an isometric view of one embodiment of this invention, with the lid of the carton raised, the platform for the cosmetics placed inside and the handle attached.

Fig. 2 is a top view of the blank from which the carton of Fig. 1 is assembled.

Fig. 3 is a section along the line 3—3 of Fig. 1.

Fig. 4 is an isometric view of the carton of Fig. 1, showing the carton completely closed, with the handle attached and in carrying position.

Fig. 5 is a view of the blank from which the top part of the platform is assembled. The platform is made in two parts which are fitted together.

Fig. 6 is a view of the blank from which the bottom part of the platform is assembled.

Fig. 7 is an isometric view of a second embodiment of this invention, with the lid of the carton raised, the platform for the cosmetics placed inside and the handle attached. The view is partly cut away.

Fig. 8 is a top view of the blank from which the carton of Fig. 7 is assembled. The piece shown in Fig. 9 is also a part of the assembled carton.

Fig. 9 is a front view of the piece which forms the rear inner wall of the carton of Fig. 7.

Referring to the drawings, the carton is generally designated by the reference numeral 1. One of the preferred embodiments is shown in Fig. 1, wherein it is apparent that carton 1 consists of a container portion and a cover portion. Platform 2 may be mounted within the container portion. Carton 1 may be equipped with carrying handle 3.

The preferred embodiment of carton 1, shown in Fig. 1, may be readily assembled from the blank

in Fig. 2. Fig. 2 is drawn substantially to the scale of this embodiment. The blank for carton 1 may be made of cardboard or other suitable material, and may be constructed from one piece of the material. In Fig. 2, solid lines represent the outline of the cut-out blank 1. Broken lines indicate the score lines along which members are articulated or along which members may be bent when the blank is assembled into carton form.

10 For convenience in describing carton 1, the members and their edges will be described as taking the positions—left, right, front, rear, top, bottom—established by the orientation of Fig. 1. In describing the positions of the cover members, 15 the cover portion shown in Fig. 1 will be assumed to be closed. It is understood, however, that the assembled carton 1 may be held in any position, such as the position shown in Fig. 4.

The bottom member of the container portion of 20 carton 1 is designated by reference numeral 4. Member 4 is substantially rectangular in shape and optionally may be square.

The side walls of the container portion of carton 1 are respectively designated by reference 25 numerals 5 and 6 and are symmetrical with respect to each other. They are articulated to member 4. When carton 1 is assembled, the front and rear edges of members 5 and 6 are perpendicular to member 4, and the top edges of members 5 and 6 slope downwardly from rear to front. Optionally, however, the top edges may be made parallel to member 4 by making the front and rear edges of members 5 and 6 equal in height.

30 The back wall of the container portion of carton 1 comprises two locking flaps which are respectively designated by reference numerals 7 and 8. Members 7 and 8 are substantially symmetrical with respect to each other, except for the different locations of slots 7a and 8a.

35 Members 7 and 8 are respectively articulated to members 5 and 6. When carton 1 is assembled, the top edges of members 7 and 8 are parallel along their entire width to member 4. The bottom edges of members 7 and 8 lie along member 4 for about half their widths but then taper away from member 4, so that the free ends of members 7 and 8 are narrower than their articulated ends.

40 Slot 8a is formed in the narrowed free end of member 8. Slot 8a comprises a notch opening on the bottom edge of member 8, which notch narrows into a slit extending upward for a substantial part of the height of said free end of member 8.

45 Slot 7a is formed in the narrowed free end of

member 1. Slot 1a comprises a notch opening on the top edge of member 1, which notch narrows into a slit extending downward for a substantial part of the height of said free end of member 8.

Slots 1a and 8a are so positioned that they are brought into registration when carton 1 is assembled. This is shown in Fig. 1.

The front corner tabs of the container portion of carton 1 are respectively designated by reference numerals 10 and 11. Members 10 and 11 are substantially rectangular and are substantially symmetrical to each other. Members 10 and 11 are respectively articulated to members 5 and 6. When carton 1 is assembled, members 10 and 11 are respectively substantially perpendicular to members 5 and 6 and lie along the front edge of member 4.

The container portion of carton 1 has a box-like front member, which is generally designated by the reference numeral 9. Member 9 comprises front wall 12, top wall 13, rear wall 14, bottom wall supports 15 and 16, and closure tab 17.

Members 12, 13 and 14 are all substantially rectangular in shape and of the same width as member 4. Member 12 is articulated to member 4. Member 13 is articulated to member 12. Member 14 is articulated to member 13.

When carton 1 is assembled, member 12 has about the same height as the front edges of members 5 and 6, while member 14 has a greater height. As a result, member 13 has approximately the same slope with respect to member 4 as the top edges of members 5 and 6. Optionally, however, members 12 and 14 may have the same height.

Members 15 and 16 are approximately rectangular in shape. Said members 15 and 16 are respectively articulated to member 14 along the left and right portions of the bottom edge of member 14.

Member 17 is articulated to member 14 along the central portion of the bottom edge of member 14. The sides of member 17 taper toward each other, and the front edge is approximately parallel to the rear edge.

The rear wall of the cover portion of carton 1 is designated by the reference numeral 19. Member 19 is articulated to member 4. Member 19 is substantially rectangular in shape, except that the side edges curve inwardly. When carton 1 is assembled, the top edge of member 19 is on a level with or slightly above the top edges of members 7 and 8. Member 19 has the same width as member 4.

The top wall of the cover portion of carton 1 is designated by the reference numeral 20. Member 20 is articulated to member 19. Member 20 is substantially rectangular in shape and is substantially as wide as member 4 and as long as the edges of members 5 and 6.

The side flaps of the cover portion of carton 1 are respectively designated by the reference numerals 21 and 22. Members 21 and 22 are substantially symmetrical with respect to each other. They are respectively articulated to the left and right edges of member 20. The bottom edges of members 21 and 22 are curved. When carton 1 is assembled and the side edges of member 20 are brought into approximate alignment with the upper edges of members 5 and 6, portions of the bottom edges of members 21 and 22 abut member 4.

The front wall of the cover portion of carton 1 is designated by the reference numeral 23.

Member 23 is articulated to member 20. Member 23 is substantially rectangular in shape, as wide as member 20 and sufficiently greater in height than member 12 to ensure proper closing of the cover portion of carton 1.

The bottom flap of the cover portion of carton 1 is designated by the reference numeral 24. Member 24 is articulated to member 23. The side edges of member 24 curve toward each other, so that the rear edge is shorter than the front edge, which is co-extensive with the bottom edge of member 23.

The closure or locking tab of the cover portion of carton 1 is designated by the reference numeral 25. Member 25 is articulated to member 24. The rear edge of member 25 is approximately one-fourth as wide as member 4. The sides of member 25 taper slightly toward each other.

Member 25 has additional transverse score lines to facilitate bending. To the rear of these score lines, locking notches 29 and 30 are cut opposite each other in the side edges of member 25.

Handle 3 may be made in any convenient manner of cardboard, plastic, cord, cloth or other suitable material. In Figs. 3 and 4, handle 3 is shown made of a loop of cardboard whose free ends are joined together by staple 3a or other suitable fastening means.

The assembly of the blank into carton 1 is shown in Figs. 2, 3 and 4. Locking flaps 7 and 8 are respectively folded upwardly along their score lines until they are perpendicular to the respective side walls 5 and 6. Side walls 5 and 6 are folded upwardly along the score lines 35 which they respectively have in common with bottom member 4. Side walls 5 and 6 are thus folded until respective slots 7a and 8a of locking flaps 7 and 8 meet. Locking flaps 7 and 8 are then locked together. The part of the free end 40 of flap 8 which is beyond slot 8a is placed behind flap 7. The part of the free end of flap 7 which is beyond slot 7a is placed behind flap 8. Side walls 5 and 6 are then perpendicular to bottom member 4. Any attempt to push side walls 5 and 6 outwardly is resisted by the locking action 45 of flaps 7 and 8. Corner flaps 10 and 11 lie perpendicular to bottom member 4 and to side walls 7 and 8. Corner flaps 10 and 11 enhance the appearance of the front of carton 1 if side walls 5 and 6 are pushed outwardly near said front corners.

Handle 3 is inserted over front support member 9. The edge of handle 3 which is above member 9 is placed against front wall member 12. Optionally, handle 3 may be omitted.

The various members comprising front support member 9 are then folded upwardly along their score lines in any convenient manner, and locking tab 17 is inserted through slot 18 in bottom member 4. As a result, front wall member 12 is substantially perpendicular to bottom member 4 and parallel to corner tabs 10 and 11. Handle 3 passes between member 12 and tabs 10 and 11. Top wall member 13 lies between side walls 5 and 6, slightly below their top edges, and has substantially the same slope. Rear wall member 14 is substantially perpendicular to bottom member 4. Bottom wall support members 15 and 16 abut bottom member 4, pass under corner flaps 10 and 11, and touch handle 3. Depending on the posi-

tion of handle 3, the members 15 and 16 may also pass under handle 3 and touch member 12.

Slot 18 is so placed that when support member 9 is folded as above described, member 13 is substantially aligned with slot 18. Therefore, tab 17 may be passed through slot 18 with no bending or with very little bending. When passed through slot 18, tab 17 is approximately perpendicular to bottom member 4. Tab 17 is then folded on its score line so that it lies along the under side of bottom member 4, with its free end facing toward the front of bottom member 4.

Slot 18 is substantially the width of the marginal score line of tab 17. Slot 18 is a straight slit, except at its ends, where it consists of little circular holes.

When it is desired to close the cover portion of carton 1, the marginal score lines of rear cover wall 19 serve as hinges. Wall 19 is brought into abutment with locking flaps 7 and 8. Side flaps 21 and 22 are folded upwardly until they are parallel to each other. Top cover wall 20 is bent toward closed position, flaps 21 and 22 being disposed inwardly of walls 5 and 6.

Front cover wall member 23 is then bent toward member 12, and bottom cover flap 24 is bent toward the under side of bottom member 4. This brings locking tab 25 into registration with slot 26 in bottom member 4. Slot 26 is in the shape of an arcuate slit, except at the ends, which are circular holes. Tab 25 is pushed through slot 26 and along the upper side of bottom member 4 until notches 29 and 30 in tab 25 lock with the outer edges of slot 26. Slot 26 is so placed in member 4 that when tab 25 is locked in slot 26, member 23 lies against member 12, and member 24 lies against member 4. Also, the outer edges of member 20 are in approximate alignment with the upper edges of members 5 and 6, and portions of the lower edges of members 21 and 22 abut member 4.

Platform 2 may be inserted in carton 1, prior to closing the cover. Platform 2 comprises upper platform member 27, which is assembled from the blank shown in Fig. 5, and lower platform member 28, which is assembled from the blank shown in Fig. 6. These blanks are cut from relatively stiff cardboard or other suitable material.

Member 27 comprises a rectangular top portion with a depending peripheral flange. Member 28 comprises a rectangular bottom portion with an upstanding peripheral flange. Member 28 nests within member 27 to form a box, the bottom portion of member 28 being flush with the bottom edge of the flange of member 27.

Various holes or cut-outs may be made in members 27 and 28, so that platform 2 will be adapted to hold containers of desired sizes and shapes.

Platform 2 is removably insertable in carton 1. Optionally, platform 2 may be fixed in place within carton 1. The bottom of platform 2 rests upon and covers substantially all of the portion of member 4 not covered by front support member 9. The height of platform 2 is somewhat less than the height of rear wall member 14 of front support member 9. Optionally, these heights may be the same.

Another embodiment of the carton, carton 1a, is shown in Fig. 7. This may be assembled from the blank shown in Fig. 8, together with the piece shown in Fig. 9. Parts of carton 1a which are similar to the corresponding parts of carton 1 are numbered the same, with addition of the suffix "a." For example, bottom member 4a of car-

ton 1a corresponds to member 4 of carton 1. Parts of carton 1a which do not thus correspond are differently numbered.

Carton 1a differs from carton 1 in the following respects:

The rear wall of carton 1a comprises locking flaps 39 and 40 and wall piece 41. Members 39 and 40 are substantially symmetrical with respect to each other and are respectively articulated to side wall members 5a and 6a. Members 39 and 40 are curved members with approximately triangular-shaped notches formed in their upper edges. The free end portions 39a and 40a of members 39 and 40 are tab portions to be used for insertion purposes.

Member 41 is substantially rectangular in shape and has two slots 41a and 41b formed therein. Slots 41a and 41b are respectively adapted to receive tab portions 39a and 40a. Slots 41a and 41b are so spaced that when carton 1a is assembled, and tab portion 39a and 40a are respectively inserted in slots 41a and 41b, walls 5a and 6a are substantially parallel to each other.

25 The brace member 42 of front support member 9a of carton 1a differs from brace members 15 and 16 of front support member 9 of carton 1. Member 42 is substantially rectangular in shape. It is articulated to member 14a and is of substantially the same width as member 14a.

In assembly, member 42 is bent so that its free lateral edge faces away from member 12a. Member 12a is thereby engaged by locking tab 43, which is punched from member 4a. Tab 43 remains secured at its upper end to member 4a.

30 The side flaps 21a and 22a of the cover portion of carton 1a, while shaped somewhat differently from their counterpart members 21 and 22, have the same functions.

35 40 No extra score lines are provided on closure or locking tab 25a. Optionally, such score lines may be added.

Preferred embodiments of this invention have been described, and optional constructions of 45 several of the members have been described. Other changes may be made without departing from the spirit and scope of this invention.

For example, front corner tabs 10 and 11 may be eliminated. Cover flaps 21 and 22 may also be 50 eliminated.

Proportions may be changed. For example, the ratio of the height of the carton to the length of the carton may be changed. Other dimensions may be changed accordingly.

55 55 Alternate means of locking the container portion of carton 1 in assembled position, besides flaps 7 and 8, and besides tabs 7 and 8 and member 41, may be used.

I claim:

60 1. A carton formed from a single blank of material, comprising a container portion and a cover portion, said container portion comprising a container bottom member, container side walls articulated to said container bottom member, the tops of said container side walls sloping from rear to front, interlocking container rear wall flaps respectively articulated to said container side walls, container front flaps articulated to said container side walls, and a container support member integral with the front of said container bottom member, said container front support member comprising a front support wall articulated to the front of said container bottom member, a top support wall articulated to said front support 65 wall, said top support wall having substan-

tially the same slope as the tops of said container side walls, a rear support wall articulated to said top support wall, bottom bracing members articulated to said rear support wall and resting in said container bottom member, and a closure tab articulated to said rear support wall, said container bottom member having a slot therein through which said closure tab is inserted, said cover portion comprising a rear cover wall articulated to said container bottom member and resting against said interlocking container rear wall flaps, a top cover wall articulated to said rear cover wall, cover side flaps articulated to said top cover wall, said cover side flaps being fitted within said container side walls and resting against said container bottom member, a front cover wall articulated to said top cover wall, said front cover wall resting against said front support wall, a cover bottom flap articulated to said front cover wall and resting against said container bottom member, and a cover locking tab articulated to said cover bottom flap, said container bottom member having a slot therein through which said cover locking tab is inserted, means for holding said cover locking tab in said inserted position, said cover locking tab resting against the inner face of said container bottom member.

2. A carton comprising a container portion and a cover portion, said container portion comprising a container bottom member, side walls, a rear wall, and a front support member, said front support member comprising a front support wall articulated to the front of said container bottom member, a top support wall articulated to said front support wall, a rear support wall articulated to said top support wall, support bracing means articulated to said rear support wall and resting on said container bottom member, and support locking means articulated to said rear support wall, said container bottom member having means integral therewith for receiving said support locking means, said cover portion comprising a rear cover wall articulated to said container bottom member, a top cover wall articulated to said rear cover wall, side cover flaps articulated to said top cover wall, a front cover wall articulated to said top cover wall, a cover bottom flap articulated to said front cover wall and resting against said container bottom member, and a cover locking tab articulated to said cover bottom flap, said container bottom member having a slot therein through which said cover locking tab is inserted, means for holding said cover locking tab in said inserted position, said cover locking tab resting against the inner face of said container bottom member.

3. A carton as in claim 2, said carton being formed from a single blank of material.

4. A carton comprising a container portion and a cover portion, said container portion comprising a container bottom member, container side walls articulated to said container bottom member, container rear wall flaps

5 respectively articulated to said container side walls, means for interlocking said container rear wall flaps, container front flaps articulated to said container side walls, and a container support member, said container support member comprising a front support wall articulated to the front of said container bottom member, a top support wall articulated to said front support wall, a rear support wall articulated to said top support wall, bottom bracing members articulated to said rear support wall and resting on said container bottom member, and support locking means articulated to said rear support wall, said container bottom wall having means integral therewith for receiving said support locking means, said cover portion comprising a rear cover wall articulated to said container bottom member, a top cover wall articulated to said rear cover wall, side cover flaps articulated to said top cover wall, a front cover wall articulated to said top cover wall, a cover bottom flap articulated to said front cover wall and resting against said container bottom member, and a cover locking tab articulated to said cover bottom flap, said container bottom member having a slot therein through which said cover locking tab is inserted, means for holding said cover locking tab in said inserted position.

5. A carton as in claim 4, said carton being formed from a single blank of material.

6. A carton comprising a container portion and a cover portion, said container portion having a base which has a front edge and a rear edge, side walls, a rear wall and a front support member, said front support member having a front support wall which is integral with the front edge of said base, a top support wall, and a rear support wall, means securing said rear support wall to said container base, said cover portion comprising a rear cover wall which is integral with the rear edge of said base, a top cover wall which is hingedly connected to said rear cover wall, a front cover wall which is hingedly connected to said top cover wall, a cover bottom flap which is hingedly connected to said front cover wall and which rests against said container base when said carton is closed, and means for releasably securing said cover bottom flap to said container base.

JACK LANG.
